THOMAS C. WILSON, OF BROOKLYN, AND ROY J. PETTY, OF NEW YORK, N. Y., ASSIGNEES TO LIQUID FUEL CUTTING & WELDING TORCH CORPORATION, OF NEW YORK, N. Y., A CORPORATION OF NEW YORK

LIQUID-FUEL TORCH

Application filed April 5, 1929. Serial No. 352,681.

This invention relates to torches of the type in which a combustible mixture of fuel and oxygen is burned with the generation of high temperature. More specifically, the present invention is concerned with a torch in which liquid fuel, such as gasoline, is employed, the liquid being vaporized in the torch and a mixture of the vapor and oxygen produced and burned at the usual tip. The new torch is primarily adapted for cutting purposes and an embodiment of the invention for that use will be illustrated and described, though it is to be understood that the principles of the invention may likewise be employed in torches for welding and other heating purposes.

While numerous attempts have been made in the past to construct torches in which a vaporized liquid is used as the combustible, these torches have not proved satisfactory. Their failure in operation may be due to various causes, but the primary reason for their lack of success is undoubtedly due to improper vaporization of the liquid and mixture of the vapor with the oxygen. Also in such torches, some effort has been made to preheat the oxygen before it mingles with the vapor, but this result, which is highly important to successful operation, has not been achieved.

The torch of the present invention has been constructed to overcome the defects of prior torches of this type and in it the liquid fuel is subjected to a high vaporizing temperature and is directed through the zone of vaporizing heat under such conditions that practically complete vaporization is accomplished with the result that no fuel in liquid form enters the chamber where mixture with the oxygen is brought about. The oxygen is also conducted to the mixing chamber in such manner that it takes up a substantial quantity of heat in the vaporizing zone and thus when it is mingled with the vapor, there is produced a combustible mixture at high temperature which is led at once to the burner tip for combustion. The mixing of the vapor and oxygen is brought about in an expansion chamber in the head where turbulent conditions exist so that a thorough mingling of the gas and vapor is obtained.

The new torch includes many novel features of construction which will be best understood from consideration of the accompanying drawings, in which

Fig. 1 is a longitudinal section of a cutting torch embodying the present invention;

Fig. 2 is a view of the torch in side elevation with parts cut away;

Figs. 3, 4, 5, 6, 7, 8, 9, and 10 are sectional views on the lines 3-3, 4-4, 5-5, 6-6, 7-7, 8-8, 9-9, 10-10 of Fig. 1;

Fig. 11 is a sectional view through a control valve on the line 11-11 of Fig. 8;

Fig. 12 is a view similar to Fig. 3 showing a modified construction;

Fig. 13 is a similar view showing a second modification; and

Figs. 14, 15, and 16 are enlarged sectional views of the preheater tip.

Referring now to the drawings, the torch will be seen to consist of a handle 20 which includes a block 21 at its rear end, a second block 22 at its front end and a metal shell 23 extending between the blocks. Extending through the block 21 are passages 24, 25, the inner walls of the passages at the outer end of the block 21 being threaded. Mounted in the threaded end of the passage 24 is a nipple 26 which can be connected to a line leading to a suitable supply of oxygen, while threaded in the end of the passage 25 is a gate valve 27 for controlling the flow of liquid fuel, such as gasoline, from a suitable container maintained under pressure. A strainer 28 is inserted in the opening at the end of passage 25 and held in place by the valve 27.

A pipe 29 extends from the block 21 to the block 22, this pipe being in communication with the passage 24. Formed in the block 21 is a cross passage 30 communicating with the passage 24, this cross passage leading to a pipe 31. Flow through the cross passage is controlled by a needle valve 32, the stem of which is threaded into a bushing 33 mounted in the block 21. Packing 33' surrounding the stem of the valve and held in place by a suitable nut makes the valve gas-tight.

A pipe 31 seated in the block 21 passes through a suitable opening in the block 22, this pipe carrying a sleeve 34 on its upper end

welded or otherwise secured in place with a gas-tight joint. Entering the sleeve is a pipe 35 which passes through a gland nut 36 threaded into the sleeve, packing 37 held in place by the nut 36 making a gas-tight joint around the pipe. The pipe 35 carries a collar 38 which is threaded into a block 39, the arrangement being such that by turning the collar 38 the pipe 35 may be moved endwise, the gland 34, 36, 37 permitting such movement while preventing the escape of gas. Oxygen flowing into passage 24 enters the pipe 31 through the side passage 30 under control of the needle valve 32 and flows through the pipe 31 to the pipe 35. Oxygen flowing into the passage 24 also enters the tube 29 leading to the head 22.

The block 22 is provided with a transverse passage 40 in communication with the pipe 29, this passage leading to a chamber 41 in the block in which is mounted a valve 42. This valve is forced against a seat at one end of the chamber by a spring 43 held in place by a nut 44, the valve having a stem 45 which extends through passage 46 in the block 22 and out through the wall of the block, a nut 47 and packing 48 preventing escape of gas around the stem. The passage 46 communicates through a transverse passage 49 with a tube 50. The valve 45 is operated by a finger piece 51 pivotally mounted on a pin 52 carried in a portion of the block 22, the depression of the finger piece unseating the valve and permitting flow from pipe 29 to pipe 50. The pipe 50 extends through the block 39 and through a similar block 53 to the burner head 54 where the end of the pipe 50 is in communication with a passage 55 in the burner head.

Liquid fuel flowing through the valve 27 passes through passage 25 and into pipe 56 which is enclosed within a pipe 56' of larger diameter which acts as a re-inforcement for the small pipe 56. The pipe 56' has a closure plate at each end between which plates pipe 56 is welded in position, the plates then being drilled for the openings of pipe 56. The pipes extend from block 21 through blocks 22 and 39 to block 53, where pipe 56 connects with passage 57. Mounted in block 53 is a tube 58 extending therefrom to burner head 54 where the end of the tube is mounted on a boss 59. Within the tube 58 is an inner tube 60 in the surface of which is cut a spiral groove 61, this groove connecting at its lower end with passage 57 in block 53, so that liquid fuel flowing through the pipe 56 passes through the passage 57 and into the spiral passage defined by the groove 61 and the inner wall of the tube 58. At the upper end of the inner

tube 60 the spiral groove leads to a circumferential channel 63, and openings 64 drilled through the bottom of the channel lead to the interior of the tube 60.

The oxygen pipe 35 extends through the inner tube 60 and fits the inner wall of the tube snugly, although it is free to be moved lengthwise by the adjusting collar 38. The oxygen tube at its free end is tapered, as indicated at 65, to a fine orifice and the tapered end of the oxygen tube enters a chamber 66 in the boss 59. The end wall of the chamber 66 is so formed that the end of the oxygen tube may be seated against it and the end of the tube and its seat in the chamber cooperate to provide a means for controlling the flow of the combustible to the burner head, since the combustible must pass through the chamber 66 between the tapered end of the tube and the wall of the chamber on its way to the burner head through the passage 67. Oxygen passing out of the nozzle end of the tube 35 also flows into the passage 67 to the burner head, the shape of the parts being such that the flow of oxygen into passage 67 induces with it combustible entering the chamber through openings 64 in the inner tube 60.

The burner head 54 is provided with an expansion chamber 68 to which the passage 67 leads and threaded into the rear wall of the expansion chamber is a tube 69, the passage through the center of the tube communicating with the passage 55 for oxygen used for cutting purposes. The tube 69 projects out through a threaded boss 70 at one end of the burner head on which boss is mounted a burner tip 71, the outer end of the tube 69 being channeled as indicated at 72 (Fig. 5). These channels cooperate with the inner surface of the burner tip 71 to provide a plurality of orifices for the combustible mixture. The tube 69 has a squared portion 73 which lies outside of the burner chamber, this squared portion permitting the tube to be threaded into and out of its recess in the burner head by means of a tool, when the burner tip 71 is removed. The tube 69 lies within the head directly in front of the passage 67 and with the inner wall of the burner head forms the annular mixing chamber 68.

A passage 74 leads from the mixing chamber 68 to a boss 75 in which is threaded a small tip 76, this tip receiving a supply of the combustible mixture from the mixing chamber 68. The tip is so positioned that the flame issuing from it strikes against the outer wall of the tube 58.

When the torch is in operation, oxygen flows through the passage 24 and thence through a transverse passage 30 and through the needle valve 32 to the tube 31, passage 30 and through the needle valve 32 to the tube 31, passing from this tube to the tube 35. Liquid fuel, such as gasoline, is admitted through the valve 27 and flows through the

tube 56 and thence through the spiral passage defined by the spiral groove 61 and the inner wall of the tube 58. By reason of this spiral passage, the flow of liquid fuel is to some extent restricted and as the fuel flows around and around through the spiral passage it is brought repeatedly under the flame issuing from the tip 76. This flame results from the combustion of gasoline vapor and oxygen and is, therefore, at a high temperature, and the repeated passage of the liquid through the hottest part of the vaporizing zone insures that all of the liquid will be vaporized. The vapor continues through the spiral passage 15 to the circumferential channel 63 and then through openings 64 into the chamber 66 in the boss 59. Oxygen flowing through the pipe 35 issues from the nozzle end 65 and passes through the chamber 66 and into passage 67 where some mixing of the oxygen and fuel vapor occurs. The mixture flows then 20 into the annular chamber 68 in the burner head where expansion takes place, resulting in a thorough intermingling of the vapor and 25 oxygen.

This mixture flows out of the burner head and into the burner tip issuing from the channels 72 to be consumed in the ordinary way. Oxygen for cutting flows through the 30 tube 29 and thence into the tube 50 under the control of valve 42. The oxygen enters the passage 55 in the head and then flows through the tube 69 to issue through the central opening 77 at the tip.

35 It will be seen that in this torch complete vaporization of the liquid fuel is assured by reason of the use of the spiral passage which causes all of the liquid to be subjected to the hottest part of the vaporizing flame a number of times in its flow to the burner head. The use of a passage of this type prevents a 40 direct flow of the liquid past the vaporizing flame, particularly when the torch is operated in a position in which the burner head is 45 below the handle.

In numerous prior torches, with which we are familiar, the liquid is conducted through a straight annular passage to the burner head, this passage being defined between an outer 50 tube and an inner tube for oxygen. Frequently asbestos or like material is placed in this passage. The presence of the asbestos is highly objectionable because it quickly becomes clogged up and in addition carbonization is likely to occur within its pores. Also, 55 since the preheating or vaporizing flame bears against one side of the tube, only that portion of the liquid which flows against the surface where the flame is playing is highly heated.

60 Liquid which flows through a part of the passage out of contact with the preheating flame is not raised to the same degree of heat and as a consequence, the liquid may be only partially vaporized at the time it enters the 65 burner head.

In the present torch, the inner tube 60 is in direct contact with the inner wall of the outer tube 58 and heat taken up from the pre-heating flame is taken up by the inner tube and passes back through the metal to the tube 35 which fits the interior of tube 58 snugly. The heat is thus conducted from the flame to the oxygen along a path of metal and it raises the temperature of the oxygen flowing through tube 35 to a high degree. 70 In prior torches with which we are familiar, the preheating of the oxygen has not been successfully accomplished because there is no metal path along which the heat may flow from the preheating flame to the oxygen. On the contrary, in those torches where the liquid flows through the annular passage surrounding the oxygen tube, the only heat which is transferred to the oxygen must be conducted through the liquid itself or through 75 its vapor. The presence of asbestos in the annular passages in these prior torches also serves no useful purpose in the transfer of heat, because of the low conductivity of this substance. In such torches, therefore, the oxygen is not raised to a high temperature, because it is effectively shielded from the pre-heating flame either by the liquid fuel or by the asbestos through which the liquid fuel 80 is flowing.

Instead of conducting the liquid fuel through the vaporizing zone along a spiral path, other methods may be employed, such, for example, as that shown in Fig. 12. In the construction there illustrated, the tube 58 surrounds a tube 78 in the outer wall of which is cut a channel 79 which extends from the block 53 nearly to the circumferential channel 63 at the forward end of tube 78. The passage 79 then turns back upon itself to conduct fuel rearwardly through the channel 80 which communicates with another channel 81 which conducts the fuel forwardly to the circumferential groove 63 whence it passes through openings 64 into the chamber 66. The tube 78 is so positioned that the channels 79, 80, and 81 extend directly through the zone where the flame from the tip 76 is playing upon the outer surface of the tube 58. The walls of the passages defined by the inner surface 100 of the tube 58 and the channels in the tube 78 form a hot plate over which the liquid fuel flows to be rapidly vaporized. In the construction shown in Fig. 12, heat is transferred from the preheating flame through tube 58, tube 78 and oxygen tube 35 to the oxygen, a metal path thus being provided by the heat transfer. 105

Instead of employing an inner tube, such as those designated 60 and 78, a coiled tube 81, such as that shown in Fig. 13, may be employed. This coiled tube is mounted at one end in the block 53 and at the other in a boss 82 extending from the burner head 54. A passage 83 in the boss leads to a cir- 110 115 120 125 130

5 circumferential channel 84 through which are formed openings 85 leading to a chamber 66. The convolutions of the tube 81 lie closely in contact with the outer wall of the tube 35 and also contact with the inner wall of the tube 58 so that in this construction also, heat from the preheating flame is conducted by 10 ly between the tube 35 and tube 66.

10 The torch is preferably made of brass, the parts being secured together by brazing or the like. For example, the tube 56 is brazed at one end in the block 21 and at the other end in the block 53. Similarly tube 50 is brazed at one end in the burner head 54, and at the other in the block 22. This construction is used throughout the torch whenever appropriate. Packing glands are also used wherever required as, for example, a gland nut 86 is threaded into a suitable opening in 15 the end of the inner tube 60 and bears against packing 87 which prevents leakage backwardly between the tube 35 and tube 66.

20 Among the important features of the new torch are the several control devices. It will be seen that the flow of oxygen to the cutting jet is controlled by the valve 42 and the supply of oxygen for combustion is controlled by the needle valve 32, this needle valve making it possible to obtain a fine degree of control of the oxygen supply for heating purposes. The fuel consumed in the new torch is under control both as a liquid and as a vapor. The fuel in liquid form passes through the gate valve 27 before it enters the 25 torch and this valve may be adjusted to provide a rough control. The fine control of the fuel supply is provided by the valve formed by the tapered end of the oxygen tube 35 and its seat in chamber 66. This valve controls the fuel in vapor form and by moving the tube 35 endwise by means of the adjustment collar 38, an exact regulation is obtained. The oxygen tube 35 is moved by regulating means disposed outside of the passage for 30 the fuel vapor, and the vapor which enters the chamber 66 flows into the passage 67 around the outside of the nozzle end of tube 35, without restriction except that provided by the parts constituting the valve. It is 35 important that there should be no threaded mounting for the oxygen tube near the burner head because at this point the parts are subjected to great heat and where a threaded mounting at this point has been provided, as in some prior torches, it has been found in practice that the threads burn out and the 40 operation of the torch is greatly impaired.

45 With the new torch, it will be seen that rapid flow of fuel through the vaporizing zone, which might result in unvaporized fuel being delivered to the burner head, is prevented, and all of the liquid is directed beneath the vaporizing flame under such conditions that perfect vaporization is obtained. 50 In torches in which the liquid passes through

asbestos in the vaporizing zone, not only does imperfect vaporization result but varying restriction to the flow of the fuel caused by different conditions in the asbestos results in a variation in pressure in the combustible mixture. Since only a portion of the combustible mixture is supplied to the preheating or vaporizing tip, variations in pressure are likely to cause the flame from this tip to be extinguished, and whenever 70 this occurs operations must be discontinued and the preheating flame reignited. In the present torch, variation in pressure in the burner head is eliminated so that the preheating flame continues to burn practically 75 indefinitely unless extinguished by drafts or the like. In order to overcome this difficulty, an igniter in the form of an asbestos cord 88 or the like is mounted in a suitable clamp 89 on the tube 58 near the burner head, the 80 clamp lying out of the zone of vaporizing temperature. The cord extends beneath the tip in such manner that it is maintained at high heat by the preheating flame and should the flame be extinguished, the cord will cause 85 it to ignite again immediately.

90 Since the successful operation of the torch depends on proper vaporization of the liquid fuel and the preheater flame must continue burning at the proper rate throughout the 95 use of the torch, it is important that the preheater tip 76 be constructed to provide a flame of the required size and that this flame should be protected against the wind. In the present torch, the tip is constructed to accomplish these results. This tip may take different forms, three of which are shown in, 100 Figs. 14, 15, and 16. As illustrated, the tip includes a stem 90 provided with threads 91 by which it can be mounted in the opening in the boss 75, the stem having a shoulder 92 with flat sides by which the tip can be engaged by a tool for insertion or removal.

105 In the tip as shown at Fig. 14, the stem is bored to provide a passage 93 lengthwise of the stem. This passage terminates close to the rear end and at this end is a fine opening 94. The passage 93 extends to a point beyond the shoulder 92 and within the end 95 of the tip, the passage increases in diameter, as indicated at 96. The portion 96 extends part way through the end 95 and leads to another portion 97 of still greater diameter. With this arrangement, the combustible mixture which flows through the passage 74 enters the tip through the fine opening 94 through which the gas passes under considerable pressure. In the passage 93 the gas expands and at the end of the passage 93 the flame begins. The hot burning gases then expand in the 110 portions 96 and 97 and the length of these portions is such that under normal operation, the cone of the flame does not project beyond the end of the tip, while the burning gases in the envelope fill such parts of the 115 120 125 130

hollow end of the tip as are not filled by the cone, the envelope spreading out beyond the end of the tip to impinge upon the surface of the tube 58.

5 In Fig. 15 a slightly modified construction is illustrated, in which the stem 90 has a passage 98 through it, this passage being connected to the open end 99 of the tip through a passage 100 of fine diameter. The open end 99 of the tip is enlarged in diameter in three stages designated 101, 102 and 103 respectively. With this arrangement, the cone of the flame appears to begin at the point where the stage 101 is connected with the stage 102, 10 the cone lying wholly within the chamber at the end of the tip, so as to be protected by the tip walls.

15 In Fig. 16, the stem 90 has a fine opening 94 at its rear end and leading forward from this opening is a passage 104 of somewhat increased diameter. This passage opens into a chamber 105, the cross-sectional area of which gradually increases as the extreme end of the tip is approached. This construction 20 is quite similar to that shown in Fig. 15 except that the chamber increases in diameter gradually instead of by steps. In any of the 25 tips illustrated, the gas flowing from the burner head flows through an orifice of small diameter beyond which the gas is allowed to expand. In each tip the cone of the preheater flame is protected to a substantial extent, the cone projecting either to only a slight extent or not at all beyond the end of the tip, 30 while the envelope around the cone fills the space at the end of the tip. Tips of the construction illustrated have been found in practice to be highly efficient and to give excellent results due to the fact that the tip can be 35 extinguished only with great difficulty.

40 By reason of the metal path for the conduction of heat from the preheating zone directly to the oxygen flowing through the tube 35, both ingredients of the combustible mixture delivered to the burner head enter the 45 expansion chamber in this head at a high temperature which is conducive to most efficient conditions of combustion at the end of the burner tip 71.

50 The tube 56 has a relatively fine bore, the cross-sectional area of which is substantially the same as the cross-sectional area of the groove 61 in the tube 60 at the end of the tube remote from the burner head. The 55 groove 61 preferably is formed so as to have an increasing cross-sectional area as the burner head is approached, thus providing space for the expansion of the vaporized fuel. The 60 cross-sectional area of the groove and of tube 56 is so fine that it has been found in practice that back-fires in the groove and tube are practically impossible. Since the tube 56 is of small diameter it is encased within the 65 outer tube 56' which serves as a stiffening

means both for tube 56 and also for the general torch structure.

What we claim is:

1. In a liquid fuel burning torch, the combination of a burner head, an oxygen pipe leading thereto, a passage for leading fuel to the head, said passage lying outside said pipe, a preheater burner receiving a combustible mixture from the burner head and directing a flame against a wall of said passage, and a metallic path for conducting heat from said flame to oxygen in the pipe. 70

2. In a liquid fuel burning torch, the combination of a preheater tip receiving a combustible mixture, an oxygen pipe, a passage lying outside the pipe, the flame from the tip impinging upon a wall of the passage, and a pathway of heat-conducting material arranged to receive heat from said flame and conduct it to the oxygen. 80

3. In a liquid fuel burning torch, the combination of a preheater tip supplied with a combustible mixture, an oxygen pipe, a burner head with which the tip communicates and to which the pipe leads, and means for conducting fuel to the head, said means being arranged to lead all of said fuel through the zone of temperature developed by a flame from said tip. 85

4. In a liquid fuel burning torch, the combination of a preheater tip providing a vaporizing flame, a mixing chamber, an oxygen pipe leading thereto, and means for conducting fuel to said chamber, said means causing all the fuel to pass through the zone of temperature developed by said flame on its way to said chamber. 95

5. In a liquid fuel burning torch, the combination of a preheater burner providing a vaporizing flame, a mixing chamber connected to said burner, an oxygen pipe leading to said chamber, and means for conducting fuel to said chamber through the zone of temperature developed by said flame, said means conducting all the fuel through said zone along a single tortuous path. 105

6. In a liquid fuel burning torch, the combination of a preheater burner providing a vaporizing flame, a mixing chamber connected to said burner, an oxygen pipe leading to said chamber, and means for conducting fuel to said chamber through the zone of temperature developed by said flame, said means including a metallic heat-conducting pathway exposed at one end to said flame and conducting heat to oxygen in said pipe. 110

7. In a liquid fuel burning torch, the combination of a preheater burner providing a vaporizing flame, a mixing chamber in communication with said burner, an oxygen pipe leading to said chamber, and a tortuous passage outside said pipe for leading all of the liquid fuel to the zone of temperature developed by said flame and leading fuel vapor from said zone to the mixing chamber. 125

8. In a liquid fuel burning torch, the combination of a preheater burner providing a vaporizing flame, a tube against which the flame impinges, a passage within the tube for conducting fuel through the zone of temperature developed by said flame, a pipe for oxygen lying within the tube, said pipe carrying a valve portion at one end, a seat with which said portion cooperates, flow from said passage being controlled by said cooperating parts, and an adjustable mounting for said pipe at a distance from said valve portion, the mounting permitting endwise movement of the tube toward and away from its seat. 10
9. In a liquid fuel burning torch, the combination of a burner head, a passage leading thereto, the wall of the passage forming a valve seat, an oxygen pipe having a tapered end adapted to cooperate with the seat to form a valve, a preheater burner in communication with said head, a passage for fuel communicating through said valve with said first passage, the flame from said burner playing on a wall of the fuel passage, and a mounting 20 for the pipe at a distance from its tapered end, this mounting affording a means for adjusting the opening of said valve. 25
10. In a liquid fuel burning torch, the combination of a burner head, a mixing chamber 30 therein, a second chamber spaced from the first and connected thereto, the wall of the second chamber being formed to provide a valve seat, an oxygen pipe movable endwise and having an end lying within the second 35 chamber, said end cooperating with said seat to form a valve, a passage for fuel leading to said second chamber, the flow thereof from the second chamber being controlled by said valve, and means engaging the tube at a distance 40 from said end for moving the tube endwise to open and close the valve. 45
11. In a liquid fuel burning torch, the combination of a burner head, a mixing chamber 50 therein, a second chamber spaced from the first and connected thereto, the wall of the second chamber being formed to provide a valve seat, an oxygen pipe movable endwise and having an end lying within the second 55 chamber, said end cooperating with said seat to form a valve, a passage for fuel leading to said second chamber, the flow thereof from the second chamber being controlled by said valve, threads carried by the tube at a distance 60 from said end, and a block having a threaded wall engaging said threads, rotation of said tube causing endwise movement thereof to open and close the valve. 65
12. In a liquid fuel burning torch, the combination of a burner head, a tube leading 60 thereto, an inner tube within said first tube, said inner tube having a channel formed in its outer surface which channel is closed by the inner wall of the first tube, a passage in the burner head connecting with one end of the channel, a mixing chamber to which the pas- 65
- sage leads, a vaporizer burner communicating with said mixing chamber and directing a flame against said first tube adjacent said channel, means for conducting liquid fuel to said channel to be vaporized therein by said flame, and a tube within said inner tube for conducting oxygen to said mixing chamber for mixture therein with the vaporized fuel. 70
13. In a liquid fuel burning torch, the combination of a burner head, a tube leading 75 thereto, an inner tube within said first tube, said inner tube having a tortuous channel formed in its outer surface which channel is closed by the inner wall of the first tube, a passage in the burner head connecting with one end of the channel, a mixing chamber to which the passage leads, a vaporizer burner communicating with said mixing chamber and directing a flame against said first tube adjacent said channel, means for conducting liquid fuel to said channel to be vaporized therein by said flame, and a tube within said inner tube for conducting oxygen to said mixing chamber for mixture therein with the vaporized fuel. 80
14. In a liquid fuel burning torch, the combination of a burner head, a tube leading thereto, an inner tube within said first tube, said inner tube having a spiral circumferential channel formed in its outer surface which channel is closed by the inner wall of the first tube, a passage in the burner head connecting with one end of the channel, a mixing chamber to which the passage leads, a vaporizer burner communicating with said mixing chamber and directing a flame against said first tube adjacent said channel, means for conducting liquid fuel to said channel to be vaporized therein by said flame, and a tube within said inner tube for conducting oxygen to said mixing chamber for mixture therein with the vaporized fuel. 85
15. In a liquid fuel burning torch, the combination of a tube, a second tube within the first and having a channel in its outer surface which channel is closed by the inner wall of the first tube to form a passage, a pipe extending through said second tube, a burner head to which said first tube is connected, said head having a chamber into which the end of said pipe projects and said passage leading to said chamber, a vaporizer burner on said head in communication with said passage, said burner directing a flame against said first tube adjacent said passage, means for admitting liquid fuel to said passage to be conducted to the zone of temperature developed by said flame for vaporization thereby, and means for admitting oxygen to said pipe. 110
16. In a torch for burning liquid fuel, the combination of a preheater burner, a passage for fuel against one wall of which the flame from said burner impinges, said passage leading all of said fuel through the hottest part of 115 120 125 130

the zone of temperature developed by said flame, and means for mixing oxygen with the fuel vaporized by said flame and supplying said burner with a part of the mixture.

5 17. In a liquid fuel burning torch, the combination of a passage for liquid fuel, a passage for oxygen adjacent thereto, a burner for directing a flame against the wall of the fuel passage to vaporize fuel flowing there-
10 through, and heat-conductive means independent of said oxygen passage for transferring heat from said flame to said oxygen.

15 18. In a liquid fuel burning torch, the combination of a passage for liquid fuel, a passage for oxygen adjacent thereto, a burner for directing a flame against the wall of the fuel passage to vaporize fuel flowing therethrough, means for mixing the vaporized fuel and oxygen, and heat conductive means
20 independent of said oxygen passage for raising the temperature of the oxygen approximately to the temperature of the vaporized fuel prior to the mixing thereof.

25 19. In a liquid fuel burning torch, the combination of a passage for liquid fuel, a passage for oxygen, means for vaporizing the liquid fuel, means receiving the vaporized fuel and oxygen and mixing them, and heat conductive means independent of said passage for oxygen for raising the temperature of the oxygen substantially to that of the vaporized fuel before the two are mixed.

30 20. In a liquid fuel burning torch, the combination of a conduit for liquid fuel, a conduit for oxygen, means for vaporizing the liquid fuel, heat conductive means independent of said conduit for oxygen for raising the temperature of the oxygen substantially to that of the vaporized fuel, and means for
35 mixing the vaporized fuel with the oxygen.

40 21. In a liquid fuel burning torch, the combination of a conduit for liquid fuel, a conduit for oxygen within said fuel conduit, burner means for vaporizing the liquid fuel, heat conductive means independent of said conduit for oxygen for raising the temperature of the oxygen substantially to that of the vaporized fuel, means for mixing the vaporized fuel with the oxygen, and means for
45 supplying the mixture to said burner means.

50 22. In a liquid fuel burning torch, the combination of a conduit for liquid fuel, a conduit for oxygen within said fuel conduit, means for vaporizing the liquid fuel, heat conductive means independent of said conduit for oxygen for raising the temperature of the oxygen to a temperature substantially the same as that of the vaporized fuel, and means for mixing the vaporized fuel and
55 heated oxygen in regulated amounts.

60 23. In a liquid fuel burning torch, the combination of a conduit for liquid fuel, a conduit for oxygen within said fuel conduit, means for vaporizing the liquid fuel and heat conductive means independent of said con-

duit for oxygen for raising the oxygen to substantially the same temperature, means for mixing the vaporized fuel and heated oxygen, and means for supplying said mixture to said vaporizing means.

65 In testimony whereof we affix our signatures. ⁷⁰

THOMAS C. WILSON.
ROY J. PETTY.

CERTIFICATE OF CORRECTION.

Patent No. 1,773,418.

Granted August 19, 1930, to

THOMAS C. WILSON ET AL.

It is hereby certified that error appears in the printed specification of the above numbered patent requiring correction as follows: Page 2, lines 126 to 128, strike out the words and comma "passage 30 and through the needle valve 32 to the tube 31, "; page 4, line 8, strike out the syllable and words "ly between the tube 35 and tube 66" and insert instead metal from the flame to the oxygen; and that the said Letters Patent should be read with these corrections therein that the same may conform to the record of the case in the Patent Office.

Signed and sealed this 7th day of October, A. D. 1930.

(Seal)

**M. J. Moore,
Acting Commissioner of Patents.**
